HYDRAULIC PUMP

Edward V. Crane, Canton, Ohio, assignor to E. W. Bliss Company, Canton, Ohio, a corporation of Delaware

Application July 1, 1954, Serial No. 440,824

1 Claim. (Cl. 103—161)

This invention relates to piston type rotary hydraulic pumps and more particularly to an improved construction of a high pressure variable delivery reversible pump.

The type of pump which embodies my invention has a cylinder barrel journaled for rotation about a fixed axis in the pump frame, the cylinder barrel having a plurality of radial cylinders with their axes inclined at a slight angle to the radii of the barrel, and pistons in the cylinders. An annular reaction ring disposed eccentrically of the axis of rotation of the cylinder barrel engages the outer ends of the pistons and causes them to reciprocate in the cylinders to pump fluid in an hydraulic system to which the pump is connected. Ports communicating with the cylinders are located to one side of the cylinder barrel and fluid being pumped flows axially through the ports to and from the cylinders. The volume of fluid pumped is varied by adjustment of the degree of eccentricity of the reaction ring relative to the axis of rotation of the cylinder barrel and the direction of fluid flow is reversed by shifting the reaction ring to the opposite side of that axis.

The large reaction forces developed within high pressure pumps create serious problems of undue and uneven wearing of the bearing surfaces of the reaction ring and of the bearings at the journals of the shaft which supports the cylinder barrel. Moreover, location of valve plates at one side of the cylinder barrel causes an axial thrust to be imposed on the cylinder barrel which tends to separate the valve plates and to cause leakage of fluid between them. Roller or ball bearings on the shaft have been used to limit such shifting of the parts but such bearings are expensive and consequently increase the cost of the pump. The problem of bearing wear is the more complex in reversible pumps of the type described because the direction in which these forces act shifts by 180° when pumping is reversed.

The pump which embodies my invention solves these problems by providing a unique system for counterbalancing the reaction forces in proportion to the magnitude of the thrust on the bearings. More specifically, I provide an hydraulic circuit through which a fraction of the fluid discharged at high pressure from the pump is fed back into the pump bearings to offset or counterbalance the radial thrust load imposed on the bearings. My invention also contemplates means for hydraulically balancing axial thrust on the cylinder barrel to prevent separation of the valve plates and thereby to eliminate substantial leakage of fluid and to improve the efficiency of the pump.

A general object of my invention is the provision of an efficient high pressure variable delivery reversible pump with means for counterbalancing radial and axial thrust loads imposed on the running parts in direct proportion to the magnitude of the loads. Another object is the provision of a reversible pump of the type described with novel means for utilizing working pressure of the pump for preventing substantial axial shifting of the rotor with-

2

in the frame thereby preventing separation of inlet and outlet valve members and escape of fluid therebetween. A further object is the provision of a reversible pump with an hydraulic system for automatically counterbalancing radial and axial thrust forces regardless of the direction of flow of fluid being pumped. Still another object is the provision of a radial pump with a side ported rotor journaled in relatively inexpensive sleeve bearings. A further object is the provision of an efficient lubrication system for a pump of the type described.

Other objects of my invention are the provision of a pump with hydraulic control for varying the volume and direction of flow of fluid pumped; the provision of bearing means for the reaction ring with the maximum area of bearing surface providing low unit pressures and minimum wear; the provision of means for hydraulically counterbalancing radial thrust on the reaction ring with a force that is radially aligned with the points of contact of the pistons with the reaction ring; the provision of novel means for feeding high pressure counterbalancing fluid to the bearing surfaces of the pump; and the provision of a compact, efficient high pressure pump that is durable and economical to manufacture.

These and other objects of my invention will become apparent from the following description of a preferred embodiment thereof reference being had to the accompanying drawings.

Figure 1 is a central vertical section of the pump taken along the axis of rotation of the shaft.

Figure 2 is a transverse section of the pump taken along the line 2—2 of Figure 1.

Figure 3 is a transverse section showing the rotatable side valve member on the cylinder barrel, the section being taken along the line 3—3 of Figure 1.

Figure 4 is a transverse section showing the stationary valve plate carried on the frame, the section being taken along the line 4—4 of Figure 1.

Figure 5 is a transverse section showing the details of construction of the bearing for the shaft, the section being taken along the line 5—5 of Figure 1.

Figure 6 is a schematic representation of the hydraulic control circuit of the pump.

A preferred embodiment of my invention is illustrated in the drawings as a pump with a frame comprising a housing 10 to which an end plate 11 is connected by bolts 12 and which has an integral mounting base 13 for anchoring the unit to a suitable support. The housing 10 and end plate 11 are axially spaced at points inwardly from their peripheries and have enlarged hub portions 14, 15 fitted with sleeve type bearings 16, 17 in which the shaft 18 carrying the rotor or cylinder barrel 19 is journaled for rotation about the axis A.

The cylinder barrel 19 has a plurality of cylinders 20 formed therein with each cylinder fitted with a piston 21 for reciprocation in the respective cylinder. In the preferred pump, the cylinder barrel has two rows of cylinders, the cylinders in each row being arranged in an annular series, and each cylinder in one row being axially aligned with a cylinder in the other row to form a pair, see Figure 2. The axes of each pair of axially aligned cylinders are parallel to each other and are inclined in an axial direction to the radius of the cylinder barrel. The inner ends of each pair of cylinders connect to an axially extending crescent shaped recess 22 which communicates through ports at the side of the cylinder barrel alternately with the main ports 24, 25 of the pump.

A plurality, nine as shown, of ports 26, one for each pair of cylinders 20, are formed at equally spaced intervals in a rotatable valve plate 27, see Figure 3, fastened to the front, right as viewed, side of the cylinder barrel

by screws 28. In juxtaposition with and engaging valve plate 27 is a stationary valve plate 30, see Figure 4, secured by screws 31 to the adjacent hub portion of the housing 10. These plates 27 and 30 have smooth planar mating side surfaces 27a and 30a, respectively, which are hardened to resist wear. Valve plate 30 has two arcuately shaped and spaced ports 32, 33 with which ports 26 of the rotatable valve plate 27 successively register as the cylinder barrel rotates about its axis. Port 32 communicates via passage 34, see Figure 2, with the main port 24, and port 33 connects to the other main port 25 by means of channel 35. Fluid to be pumped passes into the pump, for example, through port 24 and successively through channel 34, port 32 of valve plate 30, several of ports 26 of plate 27 that momentarily are registered with port 32, and into corresponding recesses 22 and cylinders 20 in the cylinder barrel. As the cylinder barrel rotates, ports 26 are successively closed by the portions 37 of plate 30 intermediate stationary ports 32, 33 and fluid trapped therein is compressed to high pressure by the inward movement of pistons 21. When rotating ports 26 successively register with stationary bottom port 33, fluid is ejected through these ports and channel 35 and main port 25 to the hydraulic circuit outside the pump.

Cylinder barrel 19 rotates about its axis A within a cradle 40 supported within the frame of the pump between the housing 10 and the end plate 11, see Figures 1 and 2. Cradle 40 has a central cylindrical bore 41 with an axis B and within which the cylinder barrel rotates. Actuation of the pistons is caused by eccentric displacement of the cradle with respect to the cylinder barrel. For this purpose the cradle is pivotally supported on the upper part of the pump frame by means of an axially extending pivot pin 44 secured in an aperture 45 in the cradle and journalled at its opposite projecting ends in embossments 46, 47 formed on the upper ends of the housing 10 and end plate 11, respectively.

Displacement of the cradle about the axis of pivot pin 44 is effected by a fluid motor 50, see Figures 1 and 2, with a piston 51 extending through a transverse recess 52 in the lower end of the cradle and connected thereto by pin 53. Opposite ends of piston 51 are slidably fitted in sleeves 55 fastened by snap rings 56 in hollow plugs 57 secured in apertures 58 in the side walls of the housing. The eccentricity of the cradle 40 with respect to the cylinder barrel, that is, adjustment of the amount of offset between the cradle and cylinder barrel axes B and A is controlled by forcing fluid into either plug 57 against the adjacent end of piston 51 and withdrawing an equal amount of fluid from the other plug through conduits 59, 60 connected to the plugs by suitable means such as the mechanism 114, see Figure 6, described below.

A bearing sleeve 62 is secured non-rotatably in bore 41 of the cradle 40 by a pair of side plates 63, see Figure 1, fastened by bolts 64 to the bearing sleeve and frictionally engaging the marginal side portions of the cradle. The inner surface 66 of sleeve 62 is cylindrical and constitutes a bearing surface for reaction ring 67 which is freely rotatable within the sleeve about cradle axis B. A radial pin 68, see Figure 2, press fitted in a radial aperture 69 in cylinder barrel 19 and slidably engaged in recess 70 in sleeve 62 locks the cylinder barrel and reaction ring together for rotation in unison. A slight clearance is provided between the side edges of the reaction ring and the plates 63 to avoid frictional drag at these places.

The width of the outer surface 71 of reaction ring 67 is substantially the same as the width of bearing sleeve 62 and hence the radial forces of reaction are distributed over a maximum bearing surface area which results in low unit pressures at this point and corresponding reduction in wear and increased life of this bearing. The inner annular surface 72 of the ring constitutes the reaction surface against which the heads 73 of the pistons

21 bear and is of lesser width, being just slightly wider than the spacing between the points of contact of the piston heads therewith. Rotation of the cylinder barrel about its axis A causes the reaction ring to rotate in synchronism therewith about the cradle axis B and eccentricity of the reaction ring with respect to the cylinder barrel by reason of the offset position of the cradle causes the pumping force to be transmitted by the reaction ring to the pistons to move same inwardly during one-half a revolution and on the other half revolution permit the pistons to move outwardly to draw fluid into the cylinders.

Reciprocation of the pistons results in uniform variation of the peripheral velocity of outer extremity of each piston which normally would cause sliding action between the piston and the reaction ring. To avoid this, the axes of the cylinders in which the pistons reciprocate are set at an angle to the radius of the cylinder barrel. The reaction ring engages each piston head 73 along the bevelled surface 74 thereof and causes the piston to roll rather than slide along the reaction surface, the piston rotating in its cylinder as it reciprocates.

As a result of this design, the bevelled heads of the two rows of pistons contact limited narrow portions of the reaction surface 72 of ring 67 which while desirable from the standpoint of eliminating sliding friction results in concentrating pumping forces transmitted by the reaction ring to this limited area of the ring surface. In order effectively to counterbalance these forces, fluid under high pressure from the discharge side of the pump is introduced between the bearing sleeve 62 and the ring 67 at the point where these forces are concentrated.

For this purpose two pairs of annular grooves 75, 76 are formed in the bearing surface 66 of sleeve 62 in substantial radial alignment with the points of contacts of the piston heads with reaction surface 72, one set of grooves 75 extending around slightly less than one-half the arcuate length of the sleeve on one side of a horizontal plane through cradle axis B, the other set 76 of corresponding length being located on the opposite side of that plane. The ends of these grooves are arcuately spaced slightly from the intersection of horizontal plane Y-Y, through cylinder barrel axis A, and the inner surface 66 of the bearing sleeve and hence either grooves 75 or grooves 76, depending on which side of the neutral or no pumping position the cradle has been adjusted, extend over that portion of the reaction ring which forces the pistons inwardly of the cylinder barrel to pump the fluid. A portion of the fluid at pump discharge pressure is directed by circuit means described below to whichever of the two sets of grooves 75, 76 is on the side of the reaction ring that transmits pumping force to the pistons and serves to counterbalance this force.

Grooves 75 are connected by channels 77 to an axially extending passage 78 in the left end, as viewed in Figure 1, of pivot pin 44 to a conduit 79 which is hydraulically connected to main port 24 of the pump. The other set of the grooves 76 is similarly hydraulically connected to the other main port 25 of the pump by means of channel 80, see Figure 2, annular groove 81 on the inner surface 41 of the cradle, channel 82, passage 83 in the right, as viewed in Figure 2, end of pivot pin 44 and conduit 85 which connects directly to port 25. Regardless of the direction in which fluid is pumped by the pump, that is to say, regardless of whether port 24 or port 25 is the high pressure port for the pump, high pressure fluid will be directed through the above described passages and channels to the proper set of grooves 75 or 76 for counterbalancing the pumping force transmitted by the reaction ring to the pistons in the cylinder barrel.

It will be noted that fluid, by this system, is directed against the outer surface of the reaction ring in substantial radial alignment with the contact of the several pistons with the reaction ring. Since the fluid for this purpose is taken from the discharge side of the pump, counter-

balancing is effected hydraulically with a force proportional in magnitude to the pumping force and which is applied directly to the portions of the reaction members which transmit this force to the pistons. In addition to this counterbalancing function, the high pressure fluid serves effectively to lubricate the bearing surfaces of sleeve 62 and ring 67 by spreading over these surfaces in a thin film which emanates from the grooves. Lubrication of the inner surface 72 of the reaction ring to minimize friction and wear at the points of contact of the piston heads with the reaction ring is facilitated by several radially formed seep holes 86 in the central portion of the ring, or, alternatively, by cooling oil circulated between and around the cylinder barrel and reaction ring.

In order to counterbalance the radial thrust imposed on the journals of shaft 18, bearings 16 and 17 are formed with circular peripheral grooves 88, 89 and 90, 91, respectively, see Figures 1 and 5, on opposite sides of the inner surfaces of the bearings for admitting fluid under working pressure to the portion of the bearing surface against which the radial thrust is directed. Channel 92 carries fluid from port 24 of the pump to groove 88 of bearing 16 and a similar channel 93 provides communication between port 25 and groove 89. Each of the peripheral grooves 88 and 89 intersects an axially extending collection groove 88', 89', respectively, located at the trailing end of the peripheral groove, the shaft being rotated in one direction only, counterclockwise as viewed, and about midway of the top and bottom of the bearing. Fluid forces into the bearing under pressure through one peripheral groove is carried between the bearing and the rotating journal surfaces to the collection groove of the other peripheral groove and hence the direction of rotation of shaft 18 determines at which end of the peripheral grooves the axial grooves are located. Fluid gathered by the collection groove passes to the opposite or low pressure inlet port of the pump.

Bearing sleeve 17 is constructed substantially the same as sleeve 16 with a similar pair of grooves 90, 91, shown in broken line in Figure 1, on the inner surface of the sleeve and each communicating with an axial groove, one of which is indicated at 90' in Figure 1. Conduits 95 and 96 connected to ports 24 and 25, respectively, communicate through channels 97, 98 in the end plate 11 with the respective peripheral grooves 90, 91 in bearing 17 and provide supply and return passages for high pressure fluid delivered to the bearing in the same manner as in bearing sleeve 16.

When the pump is in operation and the cylinder barrel is pumping fluid at high pressure into the outlet port 24 or 25, as the case may be, axially directed forces developed by the axial flow of fluid through the ports at the side of the cylinder barrel tend to cause the cylinder barrel together with shaft 18 to move slightly rearwardly, that is, to shift to the left as viewed in Figure 1, causing separation of valve plates 27 and 30 and leakage of fluid between them. To prevent this, recess 100 in hub 15 of end plate 11 within which bearing sleeve 17 is located is made longer than the journal of shaft 18 carried therein to provide a space or clearance 100a between the ends of the recess and shaft. Fluid under pressure is introduced into the space 100a through conduit 102 connected to the high pressure port of the pump and through channel 103 in end plate 11 and urges shaft 18 in the manner of a piston forwardly to the right as viewed in Figure 1, a packing seal 104 sealing the interior of bearing 17 against the end plate. The cylinder barrel and valve plate 27 carried on the shaft are likewise urged forwardly and hence valve plates 27 and 30 are pressed tightly together. Conduit 102 is connected to the high pressure or discharge port of the pump and the force which acts against the end of the shaft is directly proportional to the reaction force tending to separate the valve plates, and hence loss of fluid at this point is virtually eliminated even when the pump is working at extremely high pressures. The inner

forward edge 30b of valve plate 30 is recessed as shown in Figure 1 to fit over the end of bearing sleeve 16 and to provide an axial bearing area for valve plate 30. This bearing area is adequately lubricated by oil from bearing 16 so that the counter-balancing pressure on the end of the shaft is taken against a film of oil, thereby preventing scoring due to rubbing at this bearing area.

Figure 6 is a schematic diagram of an hydraulic circuit through which fluid is carried from the discharge side of the pump to points within the pump for counterbalancing reaction forces developed. Main port 24 is tapped by line 105 which connects to conduit 79, and line 106 is similarly connected between port 25 and conduit 85 to supply fluid under pressure for counterbalancing forces at the periphery of the reaction ring. Lines 107 and 108 connect conduits 95 and 96 with ports 24 and 25, respectively, to supply fluid for counterbalancing radial thrust at the rear, left as viewed in Figure 1, shaft journal.

Fluid to balance the axial thrust on the shaft is carried to conduit 102 by line 110 connected to ports 24 and 25, and through check valves 111 and 112 in lines 107 and 108, respectively. These check valves function to admit only high pressure fluid to line 110 when the pump is operating regardless which port, 24 or 25 is the pump discharge port. That is to say, check valves 111 and 112 insure that the working pressure of the pump always acts against the end of the shaft to counteract the tendency of valve plates 27 and 30 to separate.

Fluid for adjustably operating cradle motor 50 is obtained from a suitable source such as a servo-actuating mechanism, see Figure 6. This mechanism comprises a pump P driven by motor M and hydraulically connected to opposite ends of cradle motor 50. The line 60 to the small area of piston 51 is directly connected to pump P and hence this end of the piston is under constant pressure. Fluid is admitted to or released from the opposite end of the cradle motor by valve V connected of selective operation to link L. This link is pivotally connected at one end by suitable means to the cradle 40 and registers the position of the cradle by means of a pointer and scale 115 at the opposite end. The link is also connected to a spring centered actuating device 116 by means of which the valve V is actuated to control flow of fluid to or from one end of the cradle motor for positioning the cradle. The servo-actuating mechanism 114 is illustrative of a suitable means for controlling the direction and volume of fluid pumped and does not constitute, per se, a part of my invention.

In describing the operation of the pump, it will be assumed that shaft 18, driven by a suitable motor, causes cylinder barrel 19 to rotate in a counterclockwise direction as viewed in Figure 2, and that cradle 40 is positioned with its axis B offset to the left as viewed in Figure 2 of cylinder barrel axis A. Port 24 then becomes the inlet port and port 25 the discharge port of the pump. Fluid to be pumped enters port 24, preferably under some pressure, is drawn through port 32 in stationary valve plate 30, through the rotating ports 26 of plate 27 registered with port 32 and into the corresponding recesses 22 and cylinders 20. It will be noted that pistons 21 move outwardly during substantially the upper half arc of revolution of cylinder barrel 19, above line Y-Y of Figure 2, and draw a charge of fluid into the cylinder barrel during this half revolution. On the other half revolution, below line Y-Y, pistons 21 are moved radially inwardly and force the charge through port 33 of stationary valve plate 30 and out discharge port 25.

It will be noted the radial thrust is transmitted to pistons 21 by the portions of cradle 40 and ring 67 which are below line Y-Y. To counterbalance this thrust, a portion of the discharge fluid is transmitted by line 106, see Figure 6, conduit 85 in cradle pivot pin 44, and peripheral groove 81 in the cradle bore, into the pairs of grooves 76 in the face of bearing sleeve 62 over which reaction ring 67 passes. Since grooves 76 are radially

aligned with the points of contact of the pistons with the reaction ring, symmetrical and even balancing of the reaction forces is attained at the very points where those forces are developed.

Radial thrust is also balanced at the journals of the shaft. For bearing sleeve 16, see Figure 5, a portion of the fluid from discharge port 25 is carried by channel 93 from passage 34, communicating with port 25, to groove 89 in the lower portion of bearing sleeve 16. Similarly, high pressure fluid is carried to the lower portion of the rear bearing 17 from port 25 by line 108, see Figure 6, conduit 96, passage 98 and into groove 91 in the lower half of bearing 17. Thus fluid at a pressure proportional to the radial thrust transmitted by the shaft journals to bearings 16 and 17 is introduced between the relatively moving surfaces of the journals and bearings and effectively counterbalances the thrust. The fluid spreads as a thin film over the surfaces of the rotating journals to lubricate same and is collected in the axial grooves 88' and 90' of the respective bearings for return to inlet port 24. This system not only provides effective counterbalancing of radial thrust forces but also insures proper lubrication of the journals at the places the thrust load is maximum.

To reverse the direction of fluid flow in the primary pumping circuit, cradle 40 is offset from the cylinder barrel 18 in the opposite direction, that is, to the right as viewed in Figure 2. Port 24 then becomes the discharge port and port 25 the inlet port for the pump. Thrust forces are imposed on the opposite portions of reaction ring 67 and shaft journals of the shaft. Grooves 75 in the upper half of bearing sleeve 62 and corresponding grooves 88 and 90 in the shaft bearings, being hydraulically connected to port 24, carry fluid at discharge pressure which functions in the manner described above to counterbalance the radial thrust and to insure proper lubrication of the bearings.

Check valves 111 and 112, see Figure 6, cause fluid at discharge pressure to be impressed on the end of shaft 18 regardless of the direction of flow of fluid being pumped. When fluid is discharged from main port 25, valve 111 is closed and valve 112 is open to admit fluid at discharge pressure to line 110 and into space 100a at the rear end of the shaft. When port 24 becomes the discharge port upon reversal of direction of fluid flow, valve 112 is closed and valve 111 is open so that line 110 still carries fluid at discharge pressure. Thus the space 100a within rear journal bearing 17 always is filled with fluid from the discharge port when the pump is operating, and shaft 18, cylinder barrel 19 and valve plate 27 are urged forwardly in opposition to the axial thrust on these parts and valve plates 27 and 30 are pressed together tightly to make an efficient leak proof running seal at their respective ports.

Changes in and modifications to the above described embodiment of my invention may occur to those skilled in the art without departing from the principles and scope of the invention, and therefore I do not wish this patent to be limited precisely to the embodiment described. The scope of the patent is defined in the appended claim.

I claim:

In a pump having a frame and having inlet and discharge ports, the combination of a driving shaft having axially spaced journals, bearings for said journals supporting said shaft for rotation about an axis, one end of said shaft being journalled within said frame, a cylinder barrel fixed on said shaft and rotatable therewith, cylinders arranged in said cylinder barrel in annular series, pistons in said cylinders, axial recesses in said shaft communicating with said cylinders and extending to one side of the cylinder barrel opposite from said one end of the shaft, a rotatable valve plate fixed to said one side of the cylinder barrel and having ports communicating with said recesses respectively, a stationary valve plate carried on said frame juxtaposed with said rotatable valve plate and having a pair of diametrically opposed arcuately elongated ports communicating with said pump inlet and discharge ports, respectively, a cradle supported for pivotal movement about an axis, a reaction ring rotatably supported in said cradle and circumscribing said cylinder barrel, said cradle together with said ring being adjustable to positions eccentric to said cylinder barrel, connecting means between said cylinder barrel and said reaction ring adapted to rotate said cylinder barrel and said reaction ring in unison, said ring having an inner surface engageable with said pistons and causing same to move inwardly during one half revolution of the cylinder barrel and permitting said pistons to move outwardly during the other half revolution of the cylinder barrel whereby to pump fluid, means for hydraulically counterbalancing radial thrust on said journal bearings and on said reaction ring and axial thrust on said cylinder barrel comprising groove means between said cradle and said reaction ring hydraulically connected to the pump discharge port, said groove means extending less than 180° over the portion of said ring which forces said pistons inwardly during the pumping cycle, a groove between each journal and corresponding journal bearing hydraulically connected to said pump discharge port, each of said grooves extending over the portion of the journal which transmits the radial thrust force to the bearing, and circuit means hydraulically connecting said one end of the shaft to said discharge port for directing fluid at pump discharge pressure against said one end of the shaft to urge said shaft and cylinder barrel to move axially in the direction for pressing said valve plates together.
